PROCESS OF TREATING HYDROCARBON OILS

Application filed January 31, 1928. Serial No. 250,864.

This application is a continuation in part of the application of John C. Black and Marvin L. Chappell, filed March 10, 1927 for process of treating hydrocarbon oils, Serial No. 174,369.

This invention relates to the treatment of petroleum oils, or distillates derived from crude petroleum oil, shale oil, or similar sources, in which a certain percentage of the constituents are unsaturated hydrocarbons which have been produced by thermo cracking processes, with sulphuric acid in the presence of liquefied hydrocarbon gases dissolved in the petroleum oil at relatively low temperatures and under sufficient pressure to retain the liquefied hydrocarbon gases dissolved in the petroleum oil in a liquid state, to remove therefrom unstable and sulphur-bearing hydrocarbons without any substantial polymerization or removal of the stable unsaturated hydrocarbons, and to produce a hydrocarbon oil which will be stable without change of color or further polymerization when stored in tanks or other containers for a period of time.

By well-known methods, in the purification of naphtha or gasoline made by thermo cracking operations, much difficulty has been found in stabilizing the stock produced, without a considerable loss of the stable unsaturated hydrocarbons due to polymerization and extraction, in which sulphuric acid, caustic soda, and various oxidizing agents are usually employed. By these former well-known methods the sulphuric acid employed not only extracts the unstable hydrocarbons, but also polymerizes and extracts relatively high percentages of the stable unsaturated hydrocarbons which if conserved would be serviceable and useable for motor fuel.

By our invention these difficulties are overcome and a purified stable gasoline or naphtha stock is produced without any substantial loss of the stable unsaturated hydrocarbons by the employment of a sulphuric acid treatment on the naphtha or gasoline stock in the presence of relatively high percentages of dissolved liquefied hydrocarbon gases at relatively low temperatures. By means of this treatment with sulphuric acid at low

temperature in the presence of dissolved liquefied hydrocarbon gases the chemical action is modified and a selective action obtained, in which the sulphuric acid reacts substantially only with the unstable unsaturated hydrocarbons and sulphur bearing hydrocarbons with the formation of sulpho-acid or sludge, which is separated from the treated gasoline or naphtha, and then finished by methods well-known in the art.

An object of this invention is to accomplish a purification of gasoline or naphtha stock derived from the cracking of hydrocarbon oils, with sulphuric acid, at low temperatures and in the presence of liquefied hydrocarbon gases such as propane, butane, pentane, propylene, butylene, amylene and the like, or other hydrocarbon gases which may be derived from the gases produced in the cracking of hydrocarbon oils which are liquefiable at relatively low temperatures and relatively high pressures, and which may be utilized for obtaining low temperatures of the gasoline or naphtha stock to be treated by vaporization of a part thereof.

Another object of this invention is to purify gasoline or naphtha derived from the cracking of hydrocarbon oils with a minimum loss of the gasoline stock.

Another object of this invention is to separate low boiling gasoline stock from the gases produced in cracking hydrocarbon oil.

We are aware that it is well-known in the art to treat hydrocarbon oils at low temperatures with sulphuric acid, such methods being carried out by the employment of heat exchanger systems employing ammonia or other known refrigerating agents. Such methods, however, are not as efficient or selective in the separation of unstable and sulphur bearing hydrocarbons as are obtained by our invention.

Our invention consists in an improved method of treating gasoline or naphtha stock with sulphuric acid at low temperatures produced by internal cooling in which the refrigerating agent is employed directly in contact with the stock to be treated and also acts as a diluent to modify the reaction to the desired extent.

The easily liquefiable gases from the thermo cracking of petroleum oils, by processes such as are commercially operated for the production of synthetic gasoline, may comprise varying percentages of ethylene, propylene, butylene, amylene, hexylene, propane, butane, pentane, hexane, trimethylene, tetramethylene, pentamethylene, and the like.

In the operation of our invention, these gases are liquefied and separated from the methane gas and other gases which are not liquefiable at the temperature and pressure employed, as they come directly from the absorption tower of a cracking system by compression at pressures ranging from 100 to 300 pounds per square inch gauge and at a temperature of approximately 60 degrees F., maintained by means of a cooling and compression system of any of the well-known types. These liquefied gases are mixed with the gasoline stock to be treated in quantities sufficient to dilute the gasoline to the desired degree. The treatment of the diluted gasoline is preferably carried out at a temperature of approximately 17 degrees F. and the quantity of sulphuric acid employed may range from as low as 1 pound to as high as 40 pounds per barrel of gasoline stock, the amount employed depending upon the stock treated and the products desired.

Various further objects and advantages of the present invention will be understood from a description of a preferred process of treating hydrocarbon oils containing dissolved liquefied hydrocarbon gases with sulphuric acid at low temperatures. For this purpose, there is hereafter set forth a specific example of one form of process which embodies the invention. The process is described as it is carried out in the apparatus illustrated in the accompanying drawing.

The drawing represents a diagrammatical view of an apparatus for carrying out the invention.

Referring to the drawing, 1 indicates a pipe for conveying the gasoline or naphtha stock to be treated, from a source not shown, through a cooler or pipe heat exchanger coil 2, contained in the tank 3. 4 indicates a gauge glass connected to tank 3 for observing the oil level in the tank 3. 5 indicates a pipe or continuation of cooler coil pipe 2, which conveys the cooled oil to be treated into the bottom of treating tank 6. 7 indicates a gauge glass connected to the treating tank 6 for observing the sludge level. 56 indicates a distributor plate so that the incoming gasoline stock may be uniformly distributed as it passes up through the treating tank 6. 8 is a pipe connected to the top of treating tank 6 and conducts the oil for further treatment into the bottom of treating tank 9, which in like manner is provided with a distributor plate 10, the acid sludge level being indicated by the num-

ber 13. The sludge level in treating tank 9 is observed by means of the gauge glass 12 which is connected to said treating tank 9. 11 indicates a distributor plate in the top of treating tank 9, by means of which the sulphuric acid introduced is evenly distributed as it passes downward through the gasoline stock in the said treating tank 9. 16 is an acid tank which is filled with sulphuric acid of the desired strength through the pipe 18 which leads to a source not shown, and controlled by the valve 19. 17 is a gauge glass by means of which the level of the acid contained in said acid tank 16 may be observed. Connected to the bottom of acid tank 16 is a pipe 14 controlled by a valve 15, which is connected to the treating tank 9. 20 is a pipe connected to the top of treating tank 9 which conveys the treated cold oil into the exchanger tank 3. The exchanger 3 is provided with a dome at the top to which is connected a pipe 34 controlled by a valve 35. The pipe 34 is connected to the pipe 36 and leads to the suction side of compressor 38. 23 is a tank provided with a steam heating coil 24 controlled by valves 26 and 28, the pipe 25 leading to a source of steam not shown, and the pipe 27 leading to a steam trap not shown. The tank 23 is provided with a gauge glass 29 by means of which the level of the treated oil may be observed. The pipe 21 controlled by valve 22 connects the exchanger tank 3 to the tank 23 at the top, by means of which treated oil after cooling the incoming oil overflows into the said tank 23 where it is heated and most of the lower boiling hydrocarbons are expelled from the treated gasoline stock and then compressed to a liquid by the compressor 38 which takes suction on the top of said tank 23 through a dome as shown. Heater tank 23 is provided with an outlet pipe 31 controlled by a valve 30 which conducts the treated oil to a storage not shown. The pipe 32 is connected to the top of heater tank 23 and leads to the suction side of the compressor 38 controlled by the valve 33. 39 is a pipe connected to the discharge side of compressor 38. The pipe 39 is connected to the condenser coil 40 which is a prolongation of the pipe 39 in the condenser box 41, from where the liquefied hydrocarbon gases are conducted through a pipe 42 which is connected to a storage tank 46. The tank 46 is provided with a gauge glass 43, by means of which the level of the liquefied hydrocarbon gases may be observed. 44 is a pipe which is connected to the tank 46 at the top controlled by a valve 45 and leading to a source of liquefied hydrocarbon gases not shown. 36 is a pipe which connects the tank 46 at the top, controlled by a valve 37 which leads to the suction side of a compressor 38. 47 is a pipe controlled by valve 48 which connects the bottom of the tank 46 to pipe 5 by means of which the required

quantity of liquefied hydrocarbon gases may be introduced into the flow of gasoline stock coming through the said pipe 5. The pipe 49 connects a treating tank 6 at the bottom 5 to an acid sludge tank 51 controlled by a valve 50. The acid sludge tank 51 is connected at the top by the pipe 52 which leads to the suction side of a compressor not shown, and is employed to liquefy the hydrocarbon 10 gases given up by the sludge. 53 is a pipe controlled by valve 54, connecting treating tank 9 with treating tank 6. The pipe 61 controlled by the valve 60 represents a line for conducting the sludge to apparatus not 15 shown for recovery of the acid by methods well-known.

The preferred process as carried out with the apparatus thus described as as follows:

Petroleum oil or petroleum oil distillate, 20 such as gasoline stock made by any of the well-known cracking operations which has preferably had a preliminary treatment with caustic soda, sodium-hypochlorite or similar reagents, for the removal or partial removal 25 of hydrogen sulphide and mercaptans therefrom, is conducted from pipe 1 through cooler or exchanger coil 2 into the bottom of treating tank 6, passing through pipe 5 which is a prolongation of the heat exchanger coil 2. 30 Heat exchanger coil 2 is surrounded by the outgoing treated oil, which is maintained at approximately 17 degrees F., by taking suction on the tank 3 through the pipe 34 which leads to the suction side of a compressor 38, 35 controlled by valve 35. By means of this said suction taken on the tank 3, a portion of the lower boiling liquefied hydrocarbon gases contained in the treated oil changes to a gas, thereby cooling the treated gasoline stock 40 containing the liquefied hydrocarbon gases to a low temperature, by means of which the petroleum distillate to be treated passing through this exchanger may be cooled to the desired degree. The cooled gasoline stock 45 passing from the exchanger 3 flows into the treating tank 6 along with a regulated flow of liquefied hydrocarbon gases coming from tank 46 through the pipe 47 controlled by valve 48. The liquefied hydrocarbon gases, 50 at the rate of approximately 10 to 20 per cent by volume of the gasoline stock, which are continuously introduced along with the gasoline or naphtha stock to be treated, are maintained at approximately 17 degrees F., by 55 means of evaporating a portion of the liquefied hydrocarbon gases contained in tank 46, which is accomplished by opening the valve 37 which admits the hydrocarbon gases into the suction side of compressor 38 thereby 60 cooling the liquefied hydrocarbon gases to the desired degree. The petroleum distillate containing the required quantity of liquefied hydrocarbon gases at the required temperature passes into the treating tank 6 and 65 up through a distributor plate 56 which is

provided with openings so that the gasoline stock containing the liquefied hydrocarbon gases may pass upward in uniform streams or droplets through the sludge contained in said tank 6, whereby a partial treatment of the gasoline stock is obtained by contact with the acid sludge coming from treating tank 9. The partly treated oil containing the dissolved liquefied hydrocarbon gases passes 70 through the pipe 8 into the bottom of a second treating tank 9 where in like manner it passes through a distributing plate 10 through a body of acid and acid sludge, the level of which is indicated by the figure 13. At the same time, sulphuric acid in the desired quantities is introduced into the top of said treating tank 9 passing through the distributor plate 11 so that the same may pass downward through the oil in small droplets or streams. The acid treated gasoline stock passes out of 75 treating tank 9 through the pipe 20 and into tank 3 where the aforesaid heat exchange takes place, the acid treated cold gasoline stock absorbing a part of the heat from the incoming gasoline stock. As heretofore 80 stated, the temperature of the treated cold oil coming into the exchanger tank 3 may be further cooled by evaporating a portion of the liquefied hydrocarbons by taking suction 85 through pipe 34 which is connected to the tank 3 at the top. The treated oil passes from tank 3 into the tank 23 where the remainder of the liquefied hydrocarbon gases not suitable for gasoline stock are removed 90 by means of heating said gasoline stock to the required temperature by means of the heater coil 24 and taking suction on said tank 23 through the pipe 32 which leads to the suction side of compressor 38. The treated oil in tank 23 is conducted to a storage not shown 95 by the pipe 31 controlled by the valve 30, where said treated gasoline stock may be further treated if necessary by processes well-known in the art.

By this process the lower boiling liquefied hydrocarbon gases employed may be utilized repeatedly and only such quantities that are lost by retention in the gasoline stock or vented from the system through the valve 62 and the pipe 63, are replaced. The liquefied hydrocarbon gases evolved during the operations from the tanks 3, 23, 51 and 46 are compressed by the compressor 38 and then passed through the cooling coil 40 which is surrounded by a cooling medium contained in the condenser box 41. By this said compression and cooling, the hydrocarbon gases are liquefied and pass through the pipe 42 which is a prolongation of the cooler coil 40, connected to the tank 46.

The sulphuric acid employed in this operation may be of varying strength, depending upon the stock treated and the product desired. In case a gasoline stock containing a very high percentage of unsaturated hydro-

carbons is to be treated, the strength of the sulphuric acid employed preferably ranges from 59 to 66 degrees Bé., although in certain cases we may employ fuming sulphuric acid containing 3 to as high as 15 per cent SO_3 . For example, in the treatment of gasoline stock made by cracking a petroleum oil distillate at a pressure of approximately 1000 pounds gauge, by our process approximately 4 to 10 pounds of 3 per cent fuming sulphuric acid per barrel of the gasoline stock was required to obtain a stable water white gasoline product with a treating loss ranging from 1 to 5 per cent by volume; while by the employment of well-known methods of treating a loss of from 5 to as high as 8 per cent by volume was obtained, employing the same quantity of acid.

The acid sludge produced by this operation may be recovered by any of the well-known methods of hydrolysis and the recovered acid employed again for this treatment or for the treatment of other hydrocarbon oils.

It is to be understood that a preliminary treatment of the gasoline stock with caustic soda may not be necessary for gasoline stocks derived from a relatively low sulphur content crude petroleum oil.

It is also to be understood that this treating process may be carried out intermittently, or in batch lots, and that the treatment of the gasoline stock containing the requisite amount of liquefied hydrocarbon gases may be carried out by commingling the gasoline stock with the required amount of sulphuric acid by any other preferred or suitable method.

While the process herein described is well adapted for carrying out the objects of the present invention, it is to be understood that various modifications and changes may be made without departing from the spirit of the invention, and the invention includes all such modifications and changes as come within the scope of the appended claims.

What we claim is:

1. A process of treating gasoline or naphtha with sulphuric acid in the presence of liquefied hydrocarbon gases, comprising commingling the gasoline or naphtha containing not less than 10% by volume dissolved liquefied hydrocarbon gases at temperatures below 32 degrees F., with the requisite amount of sulphuric acid, containing not less than 76 per cent by weight sulphuric acid and then separating the products of reaction and low boiling liquefied hydrocarbon gases from the treated gasoline or naphtha.

2. A process of treating gasoline or naphtha with sulphuric acid in the presence of dissolved liquefied hydrocarbon gases, comprising commingling gasoline or naphtha containing not less than 10% by volume liquefied hydrocarbon gases with the requisite

quantity of sulphuric acid containing not less than 76 per cent by weight sulphuric acid at temperatures below 32 degrees F., and then separating the acid products of the reaction and low boiling liquefied hydrocarbon gases from the treated gasoline or naphtha. 70

3. A process of the class described, comprising treating gasoline or naphtha containing not less than 10% by volume cooled liquefied hydrocarbon gases, with sulphuric acid containing not less than 76 per cent by weight sulphuric acid at temperatures below 32 degrees F., to extract therefrom unstable hydrocarbons and sulphur bearing hydrocarbons. 75

4. A process of the class described, comprising treating gasoline or naphtha containing not less than 10% by volume dissolved lower boiling liquefied hydrocarbons, with sulphuric acid at temperatures below 32 degrees F., to extract therefrom unstable hydrocarbons and sulphur bearing hydrocarbons by a counterflow treatment in which the gasoline or naphtha reduced to the said low temperature is first commingled with lower boiling hydrocarbons and then caused to pass in counterflow contact to a sulphuric acid containing not less than 76 per cent by weight sulphuric acid reagent. 80

5. A continuous process of treating gasoline or naphtha, comprising continuously introducing and cooling the gasoline or naphtha by an exchange of heat from the treated outgoing cool gasoline or naphtha, continuously introducing into said flow of cooled gasoline or naphtha, cooled lower boiling liquefied hydrocarbon gases, causing said cooled gasoline or naphtha containing the dissolved lower boiling liquefied hydrocarbons to pass through a treating tank in counterflow to streams or droplets of sulphuric acid containing not less than 76 per cent by weight sulphuric acid, and then separating the acid sludge and the lower boiling hydrocarbons from the treated gasoline or naphtha. 95

6. A process of treating gasoline or naphtha made by cracking petroleum oils, comprising continuously introducing and cooling the gasoline or naphtha by an exchange of heat from the treated outgoing cooled gasoline or naphtha, continuously introducing into said flow of cooled gasoline or naphtha, cooled liquefied hydrocarbon gases derived from the cracking of petroleum oils, causing said cooled gasoline or naphtha containing the dissolved liquefied hydrocarbon gases to pass through a treating tank in counterflow to streams or droplets of sulphuric acid containing not less than 76 per cent by weight sulphuric acid, and then separating the acid sludge and the low boiling hydrocarbons from the treated gasoline or naphtha. 110

7. A process of treating gasoline stock made by cracking petroleum oil, comprising treating the gasoline stock with liquefied hydro- 125

carbon gases, derived from the cracking of petroleum oils, and with sulphuric acid containing not less than 76 per cent by weight sulphuric acid, at temperatures below 32 degrees F., in quantities sufficient to combine with the constituents to be separated, combining the constituents to be separated, with the sulphuric acid, and then separating the treated gasoline stock from the lower boiling liquefied hydrocarbon gases and the products of reaction.

8. A process of purifying gasoline stock made by cracking petroleum oils, comprising treating the same with liquefied gases from a petroleum oil cracking system and with sulphuric acid containing not less than 76 per cent by weight sulphuric acid at temperatures below 32 degrees F., in quantities sufficient to combine with the unstable hydrocarbons and with the sulphur bearing hydrocarbons to be separated, separating the treated gasoline stock from the acid products of the reaction, and then separating the dissolved liquefied hydrocarbon gases which are not suitable for gasoline stock, from the treated gasoline.

9. A continuous process of treating gasoline or naphtha, comprising, passing the gasoline or naphtha in heat exchange relationship with cold gasoline or naphtha subsequently produced, continuously introducing into the first mentioned gasoline or naphtha, cooled liquefied hydrocarbon gases, passing said gasoline or naphtha containing at least 10 per cent by volume of the said liquefied hydrocarbon gases, in countercurrent flow with streams of sulphuric acid containing not less than 76 per cent by weight sulphuric acid, and then separating the acid sludge formed and the liquefied hydrocarbon gases from the treated gasoline or naphtha.

10. A process of treating gasoline or naphtha derived from cracking petroleum oil, comprising, continuously passing said gasoline or naphtha in heat exchange relationship with cold gasoline or naphtha subsequently produced, introducing cooled liquefied hydrocarbon gases into said first mentioned gasoline or naphtha, passing said first mentioned gasoline or naphtha containing at least 10 per cent by volume liquefied hydrocarbon gases in counterflow with sulphuric acid containing not less than 76 per cent by weight sulphuric acid, separating the acid sludge formed and thereafter separating the liquefied hydrocarbon gases from the treated gasoline or naphtha, by distillation.

11. A method of separating unstable, unsaturated hydrocarbons from gasoline stock containing the same, comprising, subjecting the gasoline stock containing not less than 10 per cent liquefied hydrocarbon gases having boiling points less than the gasoline stock to the action of sulphuric acid containing not less than 76 per cent by weight sulphuric acid at temperatures below 32 degrees F.

12. The method of separating unstable, unsaturated hydrocarbons from stable unsaturated hydrocarbons, without removing the latter, comprising, adding liquefied hydrocarbon gases to the gasoline stock to be treated, commingling said gasoline stock containing at least 10 per cent by volume liquefied hydrocarbon gases with sulphuric acid containing not less than 76 per cent by weight sulphuric acid at temperatures below 32 degrees F., separating the treated gasoline stock from the acid sludge formed and thereafter separating the liquefied hydrocarbon gases from the said treated gasoline stock by distillation.

13. In the process of acid-treating gasoline or naphtha containing unstable unsaturated hydrocarbons to free the gasoline or naphtha from the same, the step which comprises subjecting the gasoline or naphtha at temperatures below 32 degrees F. to the action of fuming sulphuric acid in the presence of added quantities of liquefied hydrocarbon gases dissolved in the gasoline or naphtha.

14. A process of treating gasoline or naphtha with fuming sulphuric acid in the presence of liquefied hydrocarbon gases, comprising, commingling the gasoline or naphtha containing not less than 10 per cent by volume dissolved liquefied hydrocarbon gases at temperatures below 32 degrees F. with the requisite amount of fuming sulphuric acid and then separating the products of reaction and lower boiling liquefied hydrocarbon gases from the treated gasoline or naphtha.

15. A process of the class described, comprising, treating gasoline or naphtha containing not less than 10 per cent by volume of cooled liquefied hydrocarbon gases, with fuming sulphuric acid at temperatures below 32 degrees F., to extract therefrom unstable hydrocarbons and sulphur bearing hydrocarbons.

16. A continuous process of treating gasoline or naphtha, comprising, continuously introducing and cooling the gasoline or naphtha by an exchange of heat from the treated outgoing cooled gasoline or naphtha, continuously introducing into said flow of cool gasoline or naphtha, cooled lower boiling liquefied hydrocarbon gases, causing said cooled gasoline or naphtha containing the dissolved lower boiling liquefied hydrocarbons to pass through a treating tank in counterflow to streams or droplets of fuming sulphuric acid and then separating acid sludge and the lower boiling hydrocarbons from the treated gasoline or naphtha.

17. A process of purifying gasoline stock made by cracking petroleum oils, comprising, treating the same with liquefied gases from a petroleum oil cracking system and with fuming sulphuric acid at temperatures below 32 degrees F., in quantities sufficient to combine with the unstable hydrocarbons and

with the sulphur bearing hydrocarbons to be separated, separating the treated gasoline stock from the acid products of the reaction, and then separating the dissolved liquefied hydrocarbon gases which are not suitable for gasoline stock, from the treated gasoline.

5 In testimony whereof we affix our signatures.
